OSWALD HESSELBACHER AND HENRY MOESTA, OF DETROIT, MICHIGAN.

Letters Patent No. 65,809, dated June 18, 1867.

IMPROVED LEMON-SQUEEZER.

The Schedule referred to in these Letters Patent and making part of the same.

TO ALL WHOM IT MAY CONCERN:

Be it known that we, OSWALD HESSELBACHER and HENRY MOESTA, of Detroit, in the county of Wayne, and State of Michigan, have invented an improved Lemon-Squeezor; and we do declare hereby the following to be a full, clear, and exact description thereof, reference being had to the accompanying drawings, making part of the specification, in which—

Figure 1, sheet 1, is a vertical sectional view of the improved device, showing the plunger forced down into its cup.

Figure 2 is a section taken in the vertical plane indicated by red line *xx* in fig. 1.

Figure 3, sheet 2, is a sectional view, similar to fig. 1, showing the plunger elevated from its cup.

Similar letters of reference indicate corresponding parts in the several figures.

This invention relates to a new and improved device for expressing the juice from lemons, which is designed to be attached to an upright standard, operated by a lever, vibrating in a vertical plane, so that considerable pressure can be applied to the lemons without much exertion.

The nature of our invention consists in the employment of a perforated concavo-convex cup or strainer, for receiving and confining the slices of lemon during the act of expressing the juice from them, and a circular bracket, for supporting the perforated cup and keeping it in place over a vessel for receiving the juice, in conjunction with a vibrating slotted cam-lever, for raising and lowering a plunger, and applying the necessary force for expressing the juice from the slices, all being constructed as will be hereinafter described.

To enable others skilled in the art to understand our invention, we will describe its construction and operation.

The frame which supports the pressing devices, consists of a wide base, A, having a standard, B, erected upon it. This frame may be cast so as to present quite an ornamental appearance, and at the same time be light and strong. To the front part of the standard B, and at a proper distance from the base-plate A, a circular bracket, C, is applied, which is designed for receiving a flanged cup, D, and supporting this cup over a vessel put upon the stand A for receiving the lemon juice. In practice, the circular bracket C will be cast with the frame B; but if it is desired, this bracket may be cast separate, and bolted to said frame. The upper surface or edge of the bracket C is parallel, or nearly so, to the base-plate or stand A, and upon this edge the annular flange *a*, of the cup D, rests, as shown in the drawings. The cup D is of a concavo-convex form, with a suitable number of perforations through it to allow of the free escape of juice. It may be made of wood, glass, porcelain, or even of hard vulcanized rubber, and sufficiently deep to have its sides cylindrical, as shown in the drawings, for the better reception of a flanged-head plunger, E. The size and shape of the plunger E correspond to the interior cavity of the cup D, with the single exception that when the flange *e* on the plunger is brought down upon the flange *a* of the cup, there will be space left below the end of the plunger for the pulp and skin of the lemon slices after pressure, as shown in figs. 1 and 2. The flange *e* on the plunger is designed to prevent the crushing of lemon seeds, and the application of too much pressure upon the same, by its contact with the top of cup D, before the bottom of the plunger is brought fully down, as above stated. A strong plate, F, having two ears, *b b*, projecting perpendicularly from its upper side, is secured centrally to the top of the plunger E, and between these ears *b b* a segment or cam, G, works freely. The cam is slotted and formed on the end of a lever-handle, J, which is pivoted to the upper front corner of the standard B by a strong pin, *g*, as shown in figs. 1 and 3. The plunger is attached to the cam by means of a transverse pin, *g*, to which may be applied an anti-friction collar, *g'*. This pin *g* and its collar pass through the curved slot *h*, so that when the free end of the lever J is raised, the plunger will be lifted out of its cup, as shown in fig. 3, and when said lever is depressed the plunger will be depressed and brought into its cup. This arrangement affords a very powerful leverage for depressing the plunger, and also admits of ready access to the cup D, by throwing the lever J up to the position shown in fig. 1, and then raising the plunger still further, if desired, in its slot.

Having described my invention, what we claim as new, and desire to secure by Letters Patent, is—

1. The construction of the frame of a lemon-squeezor of the parts A and B, and a circular bracket, C, which latter is adapted for receiving and supporting a straining-cup, D, beneath a plunger, E, substantially as described.

2. The combination of the vibrating slotted cam-lever G J and plunger E with the cup D and its supporting segment C, constructed and arranged substantially as and for the purposes described.

O. HESSELBACHER,
HENRY MOESTA.
